EMRY A. NEWCOMB, OF KANSAS CITY, MISSOURI, ASSIGNOR TO THE ACME IRON COMPANY, OF KANSAS CITY, KANSAS, A CORPORATION OF KANSAS.

BOILER-CLEANER PRECIPITATOR.

1,199,102.

Specification of Letters Patent. Patented Sept. 26, 1916.

Application filed June 29, 1914. Serial No. 847,984.

To all whom it may concern:

Be it known that I, EMRY A. NEWCOMB, a citizen of the United States, and a resident of Kansas City, in the county of Jackson and State of Missouri, have invented a certain new and useful Improvement in Boiler-Cleaner Precipitators, of which the following is a specification.

My invention relates to improvements in boiler cleaner precipitators.

The object of my invention is to provide novel means for removing and precipitating impurities contained in the water of a steam boiler.

Another object of my invention is to provide a novel precipitating device, which will effect the quick and efficient precipitation of impurities carried by water passing through a settling chamber.

Other novel features of my invention are hereinafter fully described and claimed.

In the accompanying drawing, which illustrates the preferred embodiment of my invention, Figure 1 is a view, partly in side elevation, partly broken away, and partly in vertical section of my improved precipitating apparatus connected to a horizontal steam boiler, a part of which is shown. Fig. 2 is an enlarged cross section on the line 30 2—2 of Fig. 1.

Similar reference characters designate similar parts in the different views.

1 designates a vertical settling chamber, preferably cylindrical, and provided at its upper and lower ends respectively with heads 2 and 3.

The head 2 is provided with a central vertical screw-threaded opening 4, in which is tightly fitted a vertical screw-threaded pipe 5, the lower end of which is fitted in a screw-threaded vertical hole provided in the closed upper end of a vertical tubular member 6, preferably provided with downwardly and outwardly flaring conical sides.

The tubular member 6 is provided inside with a baffling member, which extends transversely across the lower end of the flaring portion of the member 6, and consists preferably in a hollow conical member 7, the apex of which is at the top, and the base of which is connected with the lower end of the member 6 by horizontal portions 8, Fig. 2, narrow arcuate spaces 9 being provided between the lower ends of the members 6 and 7, said spaces communicating

with the interior of the settling chamber 1, and serving as openings for conveying water and impurities carried thereby from the tubular member 6 into the settling chamber.

60

A conductor 10 is connected at one end to the upper end of the pipe 5, and extends through the top wall of the boiler 11, and inside of said boiler, as a horizontal portion 12 normally submerged by the water 13 in the boiler, and which is provided with a plurality of perforations 14 through which water passes into the horizontal portion 12. The free end of the portion 12 turns upwardly, and is adapted to extend into the steam space above the water. Said free end is normally closed by a removable cap 15. The conductor 10, outside the boiler, is provided with a shut-off valve 16.

The head 2 is provided with a lateral screw-threaded outlet opening 17, in which is fitted one end of a conductor 18, the other end of which extends through the lower side of the boiler 11. Said conductor 18 intermediate of the boiler 11 and the shut-off valve 19, is provided with a blow-off valve 20, of any ordinary character. The conductor 18 intermediate of the head 2 and the shut-off valve 19, and preferably above the upper side of the boiler 11, is provided with an air outlet 21, normally closed by a shut-off valve 22.

The lower head 3 is provided with a central discharge opening in which is fitted a discharge pipe 23 provided with a shut off valve 24, and through which, when desired, the contents of the chamber 1 may be discharged.

In the operation of my invention, the valves 24, 19 and 22 are normally closed. 95 In starting the apparatus into operation, the valve 22 is opened, thus permitting the discharge of the air from the conductors 18 and 10 and from the settling chamber 1. When water begins to discharge through the opening 21, the valve 22 is closed, after which the operation will be automatic. The water in the boiler 11 will pass by the conductor 10 into and through the pipe 5 and into the tubular member 6, which with the pipe 5 and baffling member 7 is a device for precipitating the dirt carried by the water. As the water passes through the member 6, it will be deflected outwardly by the baffling member 7 to the openings 9, through which 105 110

the water will pass into the settling chamber 1, the member 7 restraining the flow of water, which by being thus restrained and by passing into the colder portion of the chamber 1, 5 will effect a precipitation of the impurities below the member 6. By having the baffling member downwardly and outwardly flaring, the dirt will not accumulate on its upper side. By having the member 7 held 10 low on its under side, an eddy is created below it, which assists in precipitating the dirt. The water after passing from the member 6, passes upwardly between said member and the inner wall of the chamber 1, the latter being closely adjacent to said member, so that the water is again obstructed at this point, thereby further aiding in the precipitation of the dirt. The water, then clear, will now pass upwardly into the conductor 18 by which it is carried back to the boiler 11.

For the purpose of repairing the precipitator, the valves 16 and 19 are closed. At other times they remain open.

25 I do not limit my invention to the structure shown and described, as modifications within the scope of the appended claim, may

be made without departing from the spirit of my invention.

Having thus described my invention, what 30 I claim and desire to secure by Letters Patent, is:—

In a precipitator of a boiler cleaner, a settling chamber having an outlet and an inlet for water, a tubular member extending 35 vertically downwardly into said chamber through said inlet and having at its lower end below said outlet a downwardly flaring portion of less diameter than the inner diameter of said chamber, the downwardly 40 flaring portion having therein a hollow conical baffling member which flares downwardly, a water passage being provided between the lower end of the baffling member and the inner wall of the flaring portion, the 45 lower end of the conical baffling member being open.

In testimony whereof I have signed my name to this specification in presence of two subscribing witnesses.

EMRY A. NEWCOMB.
